CLAIM

The ornamental design for a wand with chiming sphere, as shown and described.

DESCRIPTION

FIG. 1 is a perspective view of a wand with chiming sphere showing my new design.

FIG. 2 is a front elevational view thereof.

FIG. 3 is a right side elevation view thereof.

FIG. 4 is a rear elevational thereof.

FIG. 5 is a left side elevational view thereof.

FIG. 6 is a top plan view thereof; and,

FIG. 7 is a bottom plan view thereof.

The broken lines in the drawing are for illustrative purposes only, and form no part of the claimed design.
